UNITED STATES PATENT OFFICE.

ALEXANDER M. ALEXANDER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FOLDING-MACHINE.

1,264,136.

Specification of Letters Patent. Patented Apr. 30, 1918.

Application filed October 26, 1914. Serial No. 868,678.

To all whom it may concern:

Be it known that I, ALEXANDER M. ALEXANDER, a citizen of the United States, residing at Beverly, in the county of Essex and State of Massachusetts, have invented certain Improvements in Folding-Machines, of which the following description, in connection with the accompanying drawings, is a specification, like reference characters on the drawings indicating like parts in the several figures.

This invention relates to folding machines and is herein illustrated in connection with a machine for progressively folding the margin of a piece of upper leather.

One feature of the invention relates to a plurality of folding members which act upon the margin of the stock successively preparatory to the pressing of the fold.

Another feature of the invention relates to improved snipping mechanism.

These and other features of the invention including certain details of construction and combinations of parts will be described in connection with an illustrative machine and pointed out in the appended claims.

Referring now to the accompanying drawing,—

Figure 1 is a side elevation of a machine in which the present invention is embodied;

Fig. 2 is a front elevation of the machine;

Fig. 3 is a perspective showing the feeding, folding and pressing members, and

Fig. 4 is a section taken on the broken line of Fig. 2 looking in the direction indicated by the arrows.

Mounted in the frame 1 of the machine is a drive shaft 3 having fast to its end a pulley 5 and from this shaft all the moving parts are driven.

Considering first the feed mechanism, the end of the shaft 3 carries an eccentric pin 7 encircled by a strap 9 which is integral with a member 11, said member being slideable in a suitable guideway in the under side of the feed member 13 whereby rotation of the shaft 3 raises and lowers said feed member. The feed member has in its end a slot 17 to receive a fixed stud 19, a spring 21 in said member serving to urge it continually toward the right as viewed in Fig. 2. Positive movement toward the left is produced by the oscillation of a lever 23 which

is pivoted at 25 to the frame and at its upper end rests against the eccentric strap 9. 55 This lever contacts near its center with an abutment 27 on an arm 29 which is pivoted at 31 to the feed member 13. The arm 29 carries at its end a roll 33 which travels in a slot in the adjusting member 35 so that 60 turning of said member raises or lowers the abutment 27 and thereby varies the extent of each intermittent feed. This feed mechanism which is of the type commonly known as a "four-motion feed" will not be further 65 described since its details of construction form no part of the present invention.

In order to hold the leather or other material down so that the feed member 13 will act upon it, an idle feed wheel 37 of frusto-conical shape is rotatably mounted in a bracket 39 carried by a rod 41. This rod is connected by a screw 43 with a plunger 45 which is continually pressed downwardly by a spring 47, a cam 51 being provided in 70 contact with the frame of the machine so that turning of said cam will raise the idle feed wheel 37 to permit the forward edge of a piece of stock to be presented to the folding mechanism. The plunger 45 fits in a 75 suitable socket in the frame of the machine, the stem of the screw 43 extending through a slot in the wall of said socket.

In the operation of the machine a portion of the margin is first turned up approximately 90° about a creaser. The turned up margin is then slotted if desired and acted upon by a supplementary folder after which the fold is pressed. A creaser 53 is herein shown as held by set screws 55 in the bracket 39, its lower operative end being substantially vertical as shown in Fig. 1. The folder which co-operates with this creaser is herein shown as a pin 57 carried by an arm 59 having a hooked end. The end of 85 this arm remote from the hook receives the stud 19 about which the arm is angularly movable. The hook rests upon a cam 61 carried at the end of the eccentric pin 7 on the drive shaft 3 and is held against said cam 90 by a spring 62. When, therefore, the drive shaft 3 is rotated the pin 57 rises intermittently and bends the margin of the stock 95 about the creaser 53.

The cutting or slitting mechanism in the 105 illustrated machine comprises two shear

members one of which is continuously vibrated and the other of which is stationary but may be adjusted toward or away from the vibratory shear member so as to cause the margin to be snipped or not as may be desired. Referring more particularly to Fig. 3, the vibratory shear member 63 and the supplementary folder 65 are shown as integral with each other and with an arm 67 which is pivoted on a fixed stud 69, said arm being in turn pivoted to a link 71. It should be noted that the side of the vibratory shear member 63 and the extension 167 of the arm 67 form a guideway to receive the stationary shear member 93. The link 71 is suspended from a pin 73 carried by the frame of the machine, there being a slot 75 in said link to receive said pin. A second curved slot 77 in the link 71 receives an actuating pin 79 which is held between spring jaws 81 on an actuating arm 85, said jaws being adjustable by means of a pinch screw 83 so as to allow a slight play between them and the pin if desired. The actuating arm 85 (see Fig. 1) is pivoted at 87 to the frame and is vibrated by means of a rod 89 the upper end of which receives a pin 91 secured in said arm and the lower end of which embraces an eccentric on the shaft 3. It will now be clear that vibration of the arm 85 causes oscillation of the link 71 and consequently oscillation of the supplementary folder 65 and the shear blade 63.

The stationary shear member 93 is pivoted to the frame at 95 and is held in place frictionally by the head of the pivot screw 95. As clearly shown in Fig. 1, this stationary shear member has a handle by which it may be moved into or out of operative position as may be desired. In said figure the full line position is the operative position and the broken line position is the inoperative position.

The presser which finally presses the fold after the action of the supplementary folder 65 is shown at 97 and is carried at the lower end of a rod 99 which is vertically slidable in bearings in the frame of the machine. The pin 79 is threaded into this rod so that when the actuating arm 85 is vibrated said rod is reciprocated.

A table 101 supports the stock as it is being fed and folded, and an edge gage 103 is adjustably mounted on said table.

The operation of the machine is as follows: With the parts in the position shown in the figures the cam 51 is turned to raise the idle feed wheel 37 to permit the forward end of a piece of stock to be placed beneath it. The cam 51 is then turned in the reverse direction whereupon the spring 47 returns the wheel 37 to the position shown. The pin 57 rises thereby turning a portion of the margin up about the creaser 53. The stock 65 is then fed along one step and acted upon by

the shear members if desired and by the supplementary folder 65. The next step of the feed brings this portion of the margin beneath the presser 97 which thereupon descends and presses the fold. Meantime succeeding portions of the margin are being acted upon by the folders and the slitting mechanism if said mechanism is in operative position. This action of the various members continues until the whole margin of the piece of stock is folded.

Although the invention has been set forth in connection with an illustrative machine it should be understood that the invention is not limited in the scope of its application to the particular machine shown and described.

Having thus described my invention, what I claim as new and desire to secure by Letters Patent is:—

1. A machine of the class described having, in combination, a support for a piece of stock, means for feeding said piece intermittently over said support, a plurality of folders movable in different directions for progressively bending a portion of the margin over the body of the stock, a presser for forcing said bent over margin against the body of the stock, and means for operating said folders and presser.

2. A machine of the class described having, in combination, a support for a piece of stock, means for feeding said piece intermittently over said support, a creaser for determining the line of fold, a folder for bending the margin of the stock up about the creaser, a supplementary folder arranged to act at an angle to the direction of action of the first named folder, means for operating said folders, and means for pressing the fold.

3. A machine of the class described having, in combination, a support for a piece of stock, means for feeding said piece intermittently over said support, a folder arranged to be moved upwardly from a position below the stock to raise a portion of the margin of said stock into an approximately upright position, a supplementary folder arranged to bend the upturned portion farther over, a presser for forcing said bent portion of the margin down upon the body of the stock, and means for operating said folders and presser.

4. A machine of the class described having, in combination, a support for a piece of stock, means for feeding said piece intermittently over said support, means for turning up the margin of said piece, a stationary shear blade, a combined vibratory folder and shear blade, a presser, and means for operating said combined folder and blade and said presser.

5. A machine of the class described having, in combination, a support for a piece of

stock, means for feeding said piece over said support, a folder for progressively bending the margin of the stock upwardly, a supplementary folder arranged to act at an angle to the direction of action of said first named folder, a pair of shear blades for slitting the margin of the stock at a location between said folders, a presser, and means for operating one of said shear blades, said folders and said presser.

6. A machine of the class described having, in combination, a support for a piece of stock, means for feeding said piece over said support, a folder for progressively bending the margin of the stock upwardly, a supplementary folder arranged to act at an angle to the direction of action of said first named folder, a movable shear blade connected with said supplementary folder, 15 a stationary shear blade arranged to coöperate with said first named blade to slit the margin of the stock, and means for operating said folders and presser.

7. A machine of the class described having, in combination, a support for a piece of stock, means for feeding said piece intermittently over said support, a stationary shear blade, a combined folder and vibratory shear blade having a guideway through 25 which said stationary blade passes, a presser located at one side of said combined mem-

ber, and means for operating said presser and combined member.

8. A machine of the class described, having, in combination, a support for a piece of stock, means for feeding said piece intermittently over said support, a movable folder arranged to turn the margin of the stock upwardly, a movable supplementary folder arranged to bend the upturned margin farther over, a presser for forcing said bent portion of the margin down upon the body of the stock, and means for operating said folders and presser.

9. A machine of the class described, having, in combination, means for feeding a piece of material intermittently into position to have its margin operated upon, a movable folder for bending said margin upwardly, a fold presser, a member located between 40 45 said folder and fold presser for bending the margin farther over prior to the pressing operation, and means for operating said folder, member and presser.

In testimony whereof I have signed my name to this specification in the presence of 50 two subscribing witnesses.

ALEXANDER M. ALEXANDER.
